FRANZ WELS, OF HOHENELBE, CZECHOSLOVAKIA, ASSIGNOR OF ONE-HALF TO CHRISTIAN KEÖNIG, OF HARTER, NEAR HOHENELBE, CZECHOSLOVAKIA

PROPELLED SCREW FOR MOTOR SLEIGHS

Application filed July 18, 1928, Serial No. 293,713, and in Austria August 19, 1927.

This invention relates to improvements in propelling screws for vehicles, such as sleighs or sledges, motor cars and the like.

It has already been proposed to drive motor-sledges or sleighs by means of screws provided with a square thread or with a thread disposed vertically with respect of the body of the screw. However sledges or sleighs furnished with a screw of this kind have not proved satisfactory for the reason hereinafter set forth.

According to the present invention the sleigh- or sledge screw is provided with a screw-thread, in which the effective screw-surface is inclined with respect to the body of the screw, preferably at 45 degrees.

In the accompanying drawings is shown diagrammatically and by way of example, in Fig. 1 a sledge screw constructed according to the present invention.

Fig. 2 illustrates in side view a motor sledge provided with an operating screw according to Fig. 1.

According to the present invention, there is provided a sledge-screw in which the pressure side of the screw-thread is inclined with respect to the body of the screw. The most favourable angle of inclination is 45 degrees.

The thrust-trajectories of the whole screw, which preferably is made of a single piece and is forced down onto the ground by its weight or by a spring or the like, pass in the direction of the arrow *c*, so that the snow, ice or the like is not pushed away or scraped off, but is compressed and forms an inclined surface of tightened or compressed snow or ice, which acts as a bearing or rest for the screw for moving forward the vehicle without any slip worth mentioning.

The ground or the lateral parts of the ground are not pushed away or scraped off neither on starting nor during driving, because at its forward end or at both of its ends the diameter of the screw is gradually reduced and thus gradually forms a screw-threaded track, which is subsequently engaged and deepened by the not reduced part of the screw, whereby the sledge is driven forward.

In order that the vehicle can travel for-

ward and backward, the thread may be undercut as shown in dotted lines in Fig. 1.

The end of the screw-face may be sharp-edged.

The screw-drive according to the present invention is suited for road-sledges, sleighs, and sledges or sleighs of any kind used for travelling on sledgy or sandy ground.

Fig. 2 illustrates diagrammatically a sledge according to the present invention, in which the screw shaft is universally connected to the driving shaft by a universal joint *d* in order to permit the sledge to travel over rough or uneven surfaces.

I claim:—

1. A propelling screw for operating on snow and ice incrusted surfaces including a body and a screw-thread on the body and the rear and front faces of the screw-thread being inclined downwardly in the direction of travel.

2. A propelling screw for operating on snow and ice incrusted surfaces comprising a body, a screw-thread on the body the effective screw surface of the thread being inclined with respect to the body and the screw-thread also being undercut, substantially as described.

In testimony whereof I affix my signature.

FRANZ WELS.
